CLYDE C. HARPSTER AND WILLIAM R. KING, OF MANSFIELD, OHIO, ASSIGNORS TO
WESTINGHOUSE ELECTRIC AND MANUFACTURING COMPANY, A CORPORATION OF
PENNSYLVANIA.

HEATING UNIT.

Application filed April 2, 1927. Serial No. 180,891.

Our invention relates to electric heaters and particularly to encased tubular heating units.

An object of our invention is to provide 5 a relatively simple and highly efficient encased tubular heating unit that may be bent to any desired shape.

In practicing our invention, we provide a tubular metal casing, an open helix of resistor wire in the casing, masses of expansively-oxidized electric-insulating material within and without said helix and a closing bushing at each end of the casing.

In the single sheet of drawings,

15 Figure 1 is a view, partially in side elevation and partially in longitudinal section, of an unfinished electric heater embodying our invention.

Fig. 2 is a fragmentary view, in longitudinal section, of an end portion of an unfinished heater, on an enlarged scale.

20 Fig. 3 is a view of an end portion, in longitudinal section, of a treated heating unit embodying our invention, on an enlarged 25 scale, and.

Fig. 4 is a view, in lateral section therethrough, taken on the line IV—IV of Fig. 3.

An electric heater, designated by the numeral 11, comprises an outer tubular metal 30 casing 12 that may be of any suitable metal which will withstand the temperature at which it is to be operated. Thus, for relatively low-temperature heaters, copper tubes may be used, and, for higher temperatures, 35 steel or special-alloy-steel tubes may be used. The tubular casing 12 should be of such dimensions, as to thickness of the wall thereof, that it can be bent into any desired shape, one form being shown in Fig. 1 as of substantially U-shape.

An open helix 13 of a suitable resistor wire, such as nichrome, is wound on a mandrel and then removed therefrom. An open helix 14 is made of a strip of metallic magnesium wound flatwise (see Fig. 2) and is located around the open helix 13 of resistor wire. A bundle 15 of rods, bars, wires or strips of metallic magnesium is located within the helix 13, a sufficient number of individual bars or strips being employed to fit relatively closely within the helix. After providing a reinforced terminal lead 16 connected to the resistor at each end thereof, which reinforcement may be made by dou-

bling over the end portion of the resistor and twisting it as shown more particularly in Figs. 2 and 3 of the drawing, the resistor helix and the magnesium elements within and without the helix are located in the tubular casing 12, substantially as shown in Fig. 60 2. We prefer to make the longitudinal extent of the helix 13 somewhat less than the overall length of the casing 12 and to make the reinforced terminals 16 extend for an appreciable distance into the end portions of 65 the casing 12.

The heating unit thus assembled is then located within an autoclave or a suitable closed casing, and subjected, for a predetermined length of time, to the action of high-temperature steam, in a manner more particularly disclosed and claimed in reissued Patent No. 16,340 to C. B. Backer. The treatment thus given will affect the condition of the initially metallic magnesium members 14 and 70 15, and expansively oxidize them into magnesium hydroxide or oxide. During this change, the initially metallic magnesium expands to substantially 200% of its initial 75 volume, so that the open helix 14 located outside of the resistor helix 13 will tightly compress the resistor within the tubular casing 12. The action of the steam upon the helix 14 of metallic magnesium, in changing it to hydroxide or oxide, is such as to change it 80 to a substantially solid crystalline tubular mass within the casing 12 and outside the helix 13, although portions of the mass of oxide will extend between the spaced turns of the resistor wire. The inner magnesium 85 member 15 will, of course, also expand and will grow outwardly, so that it will tend to open up the individual turns of the resistor wire 13 and force them outwardly against the outer tubular crystalline mass of magnesium 90 hydroxide or oxide.

The mass of magnesium hydroxide or oxide thus formed is, in effect, a relatively large crystal rather than a mass composed of a large number of individual smaller 100 crystals. This has the result of providing a highly efficient heat path from the resistor wire to the inner surface of the tubular casing 12, so that there will be only a relatively small temperature differential between the 105 resistor wire and the tubular casing itself.

The amount of initially metallic magnesium provided within the casing 12 and

closely adjacent to the ends thereof is such that it will tightly grip the reinforced terminal lead 16 to hold it securely in its proper operative position within the casing.

- 5 15 The outer ends of the casing 12 may be provided with an enlarged bore 17 in order to provide a shoulder against which the inner surface of a bushing 18 of electric-insulating material may fit. The bushing 18 has two different external diameters, and that portion having the larger diameter fits into the enlarged bore 17, substantially as shown in Figs. 2 and 3 of the drawing. The outer or extreme end portion of the casing 12 is spun over against the reduced portion of the bushing 18, as shown more particularly in Fig. 3 of the drawing, by which means the bushing 18 is firmly held in its proper operative position.
- 10 20 The use of the inner member 15 of initially metallic magnesium and finally expansively-oxidized magnesium hydroxide or oxide is important when it is desired to bend the tubular casing 12 to any form, a simple form being shown in Fig. 1, as noted above. If the inner mass of expansively-oxidized magnesium hydroxide or oxide were not provided, there would be danger of accidental contact between the spaced turns of resistor wire, at the point where the casing is bent on a small radius. This danger is entirely overcome in a device of the kind described hereinbefore.
- 25 30 35 While we have illustrated and described a device and a method embodying our invention, as applied more particularly to a tubular heating element, it is not necessarily limited thereto, as we may locate the helix of resistor wire, together with the outer and inner initially metallic magnesium members, in a suitable groove in a metal member which is to be heated and treat the same "in situ" in the manner described above in connection with these members when located in the casing 12.

40 45 Various modifications may be made in the

device embodying our invention without departing from the spirit and scope thereof, and we desire, therefore, that only such limitations shall be placed thereon as are imposed by the prior art or are specifically set forth in the appended claims.

50 55 We claim as our invention:

1. The method of manufacturing an encased tubular heating unit which comprises locating an open helix of resistor wire within an open helix of magnesium metal, locating a plurality of rods of magnesium metal within said helix and coextensive therewith, locating said resistor and magnesium members within a tubular metal casing and subjecting the assembly to the action of high-pressure steam to expansively oxidize the magnesium members into crystalline masses of electric-insulating magnesium oxide. 60

2. The method of making tubular encased heaters, which comprises locating metallic magnesium members outside and inside of an open helix of resistor wire, locating said resistor and magnesium members within a metal tube, and subjecting the assembly to the action of steam at high temperature to expansively oxidize the magnesium members to tightly hold the resistor in the metal tube and to provide a high-conductivity heat 75 path from the resistor to the metal tube.

3. A method of making a tubular heater having a heating coil that comprises placing initially metallic expansively oxidizable material within the coil and oxidizing said 80 material.

4. The method of making a tubular heater having a heating coil that comprises placing initially metallic expansively oxidizable material both within and without the coil 85 and oxidizing said material.

In testimony whereof, we have hereunto subscribed our names this 21st day of March, 1927.

CLYDE C. HARPSTER.
WILLIAM R. KING.
